UNITED STATES PATENT OFFICE.

FRANZ OSKAR SELIANOFF, OF SAN FRANCISCO, CALIFORNIA.

LOOSE-LEAF BINDER.

Application filed March 14, 1922. Serial No. 543,569.

To all whom it may concern:

Be it known that I, FRANZ OSKAR SELIANOFF, a citizen of the United States, residing at the city and county of San Francisco and State of California, have invented new and useful Improvements in Loose-Leaf Binders, of which the following is a specification.

This invention relates to loose leaf binders 10 of the ring type, that is, one having curved or ring-like fasteners rather than the straight or post type.

A common fault with binders of this type is that the leaves catch or bind upon 15 the rings and become torn; also they tend to spread out along the rings and prevent the covers of the binder from fully closing. I overcome this trouble in the present invention by using a plurality of narrow filling strips between each cover and the stack of leaves whereby to retain the leaves in compact form at their inner edges and cause them to occupy the front portion 20 of the rings.

One form which my invention may assume is exemplified in the following description and illustrated in the accompanying drawings, in which—

Fig. 1 shows a sectional view of a loose 30 leaf binder in open position and fitted with filling strips according to my invention.

Fig. 2 shows a sectional view of the same in closed position; and

Fig. 3 shows a perspective view of one 35 of the filling strips.

For the purposes of illustration, I show a conventional type of binder comprising covers 10, back plate 11 and fastening rings 12. These rings are split at 13 and are held 40 in closed position by any suitable form of spring means. Loose leaves 14 having holding holes 15 at their inner margins are arranged upon the rings, being freely slideable thereon. Between each cover and the stack 45 of leaves I arrange a plurality of filling strips 16, which are in the form of narrow strips of comparatively heavy paper having reinforced eyelets 17 to fit upon the fastening rings 12.

These strips serve to force the loose leaves 50 into compact position at their inner edges,

as best illustrated in Fig. 2. It will be seen that the loose leaves are caused to occupy a position at the front of the fastening rings so that the back covers may be closed flat. Without these filling strips the leaves tend to climb back upon the rings and prevent the cover from closing. Also without the filling strips the leaves tend to get out of alignment and catch or bind upon the rings, with danger of tearing or mutilating the leaves. It will be noted that the strips are so narrow as not to interfere with the closing of the covers even when the strips are disposed edgewise with relation to the covers.

The number of strips 16 can be varied to suit the conditions of the book, that is to say, where the book contains a relatively small number of leaves, then a larger number of filling strips should be used than would be the case where the book is fairly well filled with leaves.

Having thus described my invention, what I claim and desire to secure by Letters Patent is:

1. A loose leaf binder comprising covers, a back strip, fastening rings on the back strip to receive and retain loose leaves in place between the covers and a plurality of separately removable filling strips arranged upon the rings between each cover and stack of leaves for the purpose mentioned.

2. A loose leaf binder comprising covers, a back strip, fastening rings on the back strip movable apart to receive loose leaves in place thereon and a plurality of narrow strips formed with reinforced eyelets to fit over the rings and arranged between each cover and stack of leaves to force the leaves forwardly upon the rings and compress their inner edges.

3. A loose leaf binder comprising covers, a back strip, fastening rings on the back strip to receive and retain loose leaves in place between the covers, and a relatively narrow filling strip formed with eyelets to fit over the rings and arranged between each cover and the stack of leaves whereby to force the leaves forwardly upon the rings and compress their inner edges.

4. In combination with a loose leaf binder

having covers connected by a back strip and split rings supported by the back strip for receiving and retaining loose leaves in place between the covers, of a plurality of comparatively narrow strips having eyelets along their longitudinal center to fit over the rings whereby the strips may be arranged between

each cover and the stack of leaves, said strips adapted to maintain the leaves forwardly upon the rings, and to be parallel with the leaves only when the binder covers are open.

FRANZ OSKAR SELIANOFF.
